UNITED STATES PATENT OFFICE.

MORRIS J. STERN, OF JAMAICA, NEW YORK.

DESIGN FOR A JEWEL MOUNT.

Application filed November 4, 1922. Serial No. 4,226. Term of patent 3½ years.

To all whom it may concern:

Be it known that I, MORRIS J. STERN, a citizen of the United States, residing at Jamaica, in the county of Queens and State of New York, have invented a new, original, and ornamental Design for Jewel Mounts, of which the following is a specification, reference being had to the accompanying drawing, forming part thereof.

Fig. 1, is a top plan view;

Fig. 2, is a side elevation; and

Fig. 3, a bottom plan view, of a jewel mount, showing my new design.

I claim:

The ornamental design for a jewel mount, as shown.

MORRIS J. STERN.
